UNITED STATES PATENT OFFICE.

EUGENE W. HAWLEY, OF PHILADELPHIA, PENNSYLVANIA.

WARDROBE TRUNK.

Application filed December 12, 1923. Serial No. 620,080.

To all whom it may concern:

Be it known that I, EUGENE W. HAWLEY, a citizen of the United States, residing at Philadelphia, county of Philadelphia, and 5 State of Pennsylvania, have invented a new and useful Improvement in Wardrobe Trunks, of which the following is a full, clear, and exact description, reference being had to the accompanying drawings, which form a part of this specification.

In wardrobe trunks, it is customary to provide one compartment with drawers and another with clothing supports and also, frequently, with a swingable and removable 15 shoe box. A typical clothing supporter construction comprises a pair of telescoping rods extending forward from the rear of the trunk compartment and separate and removable wooden hangers adapted to rest 20 and slide on such rods. Wardrobe trunks are frequently used as substitutes for closets or wardrobes, especially when the user is traveling from place to place. In such cases, it is convenient to allow the trunk to 25 remain in its open position. However, it is objectionable to allow the contents of the clothing compartment to be exposed to view, and therefore, this compartment has been provided with a cover that extends 30 across the front of the compartment. Such covers must, of course, be removable to secure access to the articles of wearing apparel behind them.

The object of my invention is to provide 35 a cover or curtain which will effectively serve the purpose of concealing the clothing, which is permanently attached to the trunk, which occupies a minimum of space when not in use, and which is readily manipulatable to apply and remove.

A preferred embodiment of the invention is shown in the accompanying drawings, in which—

Fig. 1 is a perspective view of a wardrobe trunk in open position, with cover or curtain in unrolled or operative position.

Fig. 2 is a perspective view of the top of the garment compartment of the trunk.

Fig. 3 is a front elevation of the garment 50 compartment, with the cover or curtain rolled up.

Fig. 4 is a perspective view of the means for holding the cover or curtain in operative position.

Fig. 5 is a section through the cover or

curtain and its supporting and guiding mechanism.

Fig. 6 is a partial front view of said supporting and guiding mechanism.

The trunk comprises the compartments *a* and *b* hinged together in the usual way. The clothing compartment *b* carries telescopic supporting rods *c*, *c*, having front stop *d*, *d*, and slidably supported, removable, wooden hangers *e*, *e*. The compartment *a* is provided with vertical reinforcing bars *f*, *f* extending along opposite front edges from the bottom to nearly the extreme top, and these bars carry vertical guide-ways *g*, *g*, adapted to be slidably engaged by members on a shoe box *h*.

The compartment *a* is provided with a lid or arched top *i* hinged to the top of the rear wall of the compartment. This top has side members *j*, *j* and also a front piece *k* whose lower edge is substantially above the lower edges of the side pieces *j*, *j*.

Between the side walls of the hinged top, a short distance back of its front edges, extends a tubular roller *m* supported at opposite ends in a manner similar to any ordinary shade roller and similarly provided with a coiled spring or springs *n* and having similarly secured to it the end of a flexible shade, cover or curtain *o*, which is coiled about it in the usual way. The specific construction of such shades is so well known that more specific description and illustration are unnecessary. Indeed, it is preferred that the ordinary construction be simplified by the omission of the means commonly provided to allow the shade to be held in various partially unrolled positions, and such means are therefore not illustrated.

Secured against the lower face of the front piece *k* of the top and against the front margins of the side walls *j*, *j* of the top, is a yoke-shaped bar *p*. Extending across the front of the top *i* and secured at opposite ends to the depending members of the yoke *p* is a rod *r* on which is sleeved a turnable guide roller *s*.

It will be noted that the roller *s* is located in front of and spaced from the roller *m* and that the curtain *o* extends from the roller *m* up over the rollers *s* and thence down in front of the roller *s*. The roller *s* therefore acts as a guide for the cover *o*. It is impracticable to position the roller *m*

at or very near the extreme front of the top *i*, as if so positioned, the cover or curtain coiled thereon, upon the dropping of the top, would strike the stops *d* on the telescoping rods *c*. If the roller *o* were positioned as shown and the guide *s* omitted, the curtain could not clear the upper ends of the bars *f*. It would be impossible to secure the curtain roller to the fixed compartment *a*, as it would prevent the withdrawal toward the front of the hangers or the garments suspended therefrom. By the arrangement described, the curtain roller is so positioned as not to interfere with the manipulation of the clothes, and, in the closing of the top or lid, not to engage any part of the garment suspending structure, while when the curtain is completely unrolled it extends, throughout its exposed height, along the extreme front of the clothing compartment in a vertical plane.

The lower end of the curtain carries a cross-bar *t*, which, when the curtain is pulled down to its lowest position, may be slipped into the socket formed by the angle clips *u*, *u*, and thereby held from rolling up under the action of its operating spring.

It is preferred to make the curtain of a length just sufficient to overlap the top of the shoe box *h*. The shoe box itself conceals the lower part of the compartment, so that the shoe box and the curtain together, when the former is positioned and the latter unrolled, completely cover the clothing compartment.

Having now fully described my invention, what I claim and desire to protect by Letters Patent is:

1. In a wardrobe trunk, the combination with one compartment thereof, of garment-supporting devices therein, a lid pivoted thereto and adapted to be moved to open and close the top of the compartment, a spring roller carried by said lid, a curtain adapted to be rolled on the roller and un-

rolled therefrom, a guide secured to the lid in front of the roller, and means for securing the end of the curtain when unrolled, the curtain extending from its roller forwardly over said guide and thence downward, said guide being so positioned that when the lid is closed, the unrolled curtain will extend downward from the guide in a substantially vertical plane.

2. In a wardrobe trunk, the combination with one compartment thereof, of garment-supporting devices therein, a lid hinged to the rear of said compartment, a spring roller carried by said lid and so spaced from the front of the lid as to clear said garment-supporting devices upon closure of the lid, a guide secured to the lid adjacent its front edge and in front of and spaced from the curtain support, and a roller to be rolled on and unrolled from the roller, and means for securing the end of the curtain when unrolled, the curtain extending from its support forwardly over said guide and thence downward.

3. In a wardrobe trunk, the combination with one compartment thereof, of garment-supporting devices therein, a lid adapted to be moved to open and close the top of the compartment, a spring roller carried by said lid, a curtain adapted, when the lid is closed, to be unrolled from said roller and pulled down to about the level of the top of the shoe box, whereby, when the lid is closed and the curtain unrolled and so pulled down, the lid, shoe box and the curtain together provide a front cover for the compartment, and a guide for the curtain in front of the roller which also forms a stop for the curtain when rolled up by the spring roller.

In testimony of which invention, I have hereunto set my hand, at Woodbury, New Jersey, on this 6th day of December, 1923.

EUGENE W. HAWLEY.
